UNITED STATES PATENT OFFICE.

GIACOMO SERVADIO, OF NEWPORT, RHODE ISLAND.

DESIGN FOR A BOOTH.

SPECIFICATION forming part of Design No. 23,478, dated July 17, 1894.

Application filed May 18, 1894. Serial No. 511,723. Term of patent 7 years.

To all whom it may concern:

Be it known that I, GIACOMO SERVADIO, a subject of the King of Italy, residing at Newport, Rhode Island, have invented and produced a new and original Design for Booths for the Sale of Articles upon the Streets and in the Parks of Cities, of which the following is a specification.

In the accompanying drawing the figure is 10 an elevation with the door upon one side open.

The leading feature of my design consists in the shape and configuration of the booth and will be more fully described.

The booth is provided with a base *a*, and is 15 eight sided, four of the sides as at *b*, making up the booth proper while the other four sides *c*, are simply the corners cut off at an angle to the sides *b*. The lower part of the sides *b*, are closed while the upper parts are provided 20 with windows adapted to be raised and low-

ered. On each of the corners or sides *c*, projects a receptacle *d*, with a closed front. At the base of each window in the sides *b*, is a projecting ledge *e*. At the top of the booth is an ornamental railing *f*, and above this 25 railing a series of panels are provided, and above the panels there is an ornamental cap piece resting upon a plate provided with a fringed covering *g*. The cap piece is surrounded by an ornament *h*. 30

I claim—

The design for a booth herein shown and described.

In testimony whereof I affix my signature in presence of two witnesses.

GIACOMO SERVADIO.
